(57) **CLAIM**

I claim the ornamental design for a hollow ball having openings distributed about exterior surface, as shown.

DESCRIPTION

FIG. 1 is a perspective view of a hollow ball having openings distributed about exterior surface in accordance with the present invention;

FIG. 2 is a front elevational view thereof, the rear elevational view is identical; and,

FIG. 3 is a top plan view thereof, the bottom plan view, the left side elevational view and the right side elevational view are identical.
